EXERCISING DEVICE

Goodwin Lyon, 524 N. Bundy Drive,
Los Angeles, Calif. 90049

Filed May 2, 1968, Ser. No. 11,750

Term of patent 14 years

Int. Cl. D21—03

U.S. Cl. D34—5

I claim:

The ornamental design for an exercising device, substantially designed as shown.
